STACKING APPARATUS

Erich Widmer, Visp, Wallis, Switzerland, assignor to
Lenza Electric and Chemical Works Limited, Gampel,
Wallis, Switzerland

Filed May 4, 1960, Ser. No. 26,739

Claims priority, application Switzerland May 26, 1959
30 Claims. (Cl. 214—6)

The present invention relates to a stacking apparatus which is particularly suitable for depositing bulky objects, such as heavy sacks and the like, in one or more vertical stacks. More particularly, the invention relates to an apparatus which may be utilized for automatically stacking objects, delivered at predetermined intervals by a supply conveyor or the like, onto a receiving platform or another type of storing means in one, two, three or even more rows.

An important object of the present invention is to provide a stacking apparatus which is adapted to stack the objects at the same rate at which the objects are delivered thereto so that no pileup of goods will take place at the stacking station.

Another important object of the invention is to provide a stacking apparatus which is particularly suitable for stacking of comparatively flat objects, which may be utilized for depositing the objects in one, two, three or more stacks, and which may be readily adapted for stacking of differently dimensioned and configurated objects.

A further object of the invention is to provide a stacking apparatus of the above outlined characteristics whose operation is fully automatic in that it may be operated in a required rhythm by the oncoming objects and which, therefore, requires no attention once it is set in operation.

An additional object of the instant invention is to provide a stacking apparatus which is of very compact design and which, therefore, occupies very little space in a plant or another installation where it is put to use.

A concomitant object of the invention is to provide a stacking apparatus of the above described type which is constructed and assembled in such a way that it may deposit the objects in any desired position, i.e. which may invert the objects or which may deposit the objects in the same position which the objects assume prior to the stacking operation.

An additional object of the invention is to provide a stacking apparatus of the above outlined characteristics which is constructed and assembled in such a way that the objects will not suffer any damage during passage through the apparatus and during deposition in one or more stacks on a platform or the like.

Still another object of the present invention is to provide a stacking apparatus which may be automatically arrested when the stacks of objects reach a required height.

A further object of my invention is to provide a stacking apparatus of the above outlined type which is of very rugged construction and which may be utilized for stacking of comparatively heavy or comparatively lightweight objects.

A more specific object of the invention is to provide an arrangement of improved loading or stacking members

2

which are connected and mounted in such a way that they automatically receive, guide and discharge one or more objects in a continuous operation without necessitating manual control or assistance by one or more attendants at any stage of the operation.

With the above objects in view, the invention resides in the provision of a stacking apparatus which, in its elementary form, comprises a pair of loading members connected to each other in such a way that one pivots in clockwise direction when the other pivots anticlockwise, and vice versa, as well as means which alternately pivots the loading members into a first position in which the loading members define an upwardly opening compartment which may receive an object, and thereupon into a second position in which the upwardly opening compartment is transformed into a downwardly opening compartment so that the object may drop onto a platform, into a receptacle or into any other suitable receiving means. Each object is preferably deposited in at least nearly horizontal position; to that end, the one or both loading members are formed with retaining means and with plate-like main body portions which guide the objects from a substantially vertical position when the objects are received in the upwardly opening compartment into a substantially horizontal position during the transformation of upwardly opening compartment into the downwardly opening compartment, the objects thereupon dropping by gravity onto the receiving means.

The frame which mounts the loading members and their shafts may be swung between a central position in which the loading members deposit a central stack and one or more additional positions in which the loading members deposit additional stacks of objects, for example, a first stack at one side and a second stack at the other side of the central stack.

Alternately, the stacking apparatus may comprise three loading members which are connected with each other in such a way that the central loading member defines an upwardly opening first compartment with say the left-hand loading member and that the central loading member simultaneously defines a downwardly opening second compartment with the right-hand loading member. Such arrangement is preferred when the apparatus is utilized for continuously depositing goods in two vertical stacks and constitutes a considerable simplification insofar as the frame of the loading members may remain stationary. An object received in the first compartment is then discharged after the first compartment is transformed into a downwardly opening third compartment, and the second compartment is simultaneously transformed into an upwardly opening fourth compartment which is ready to receive a second object from a supply conveyor or the like. A single supply conveyor may deliver objects to the first and fourth compartments of such stacking machines.

Certain other features of the improved apparatus reside in the provision of means for automatically pivoting the loading members into their respective positions in response to the advance of objects along and toward the discharge end of the supply conveyor, in the provision of means for automatically swinging the frame between a central and one or more additional positions, in the provision of means for automatically lowering the object receiving means away from the loading members as the height of stacks on the object receiving means increases,

in the provision of specific pivoting means for the loading members, and in the provision of means which swings the frame in such a way that the loading members may deposit objects at a slant in order to avoid a collapsing of comparatively high stacks.

The novel features which are considered as characteristic of the invention are set forth in particular in the appended claims. The invention itself, however, both as to its construction and its method of operation, together with additional objects and advantages thereof, will be best understood from the following detailed description of certain specific embodiments when read in connection with the accompanying drawings, in which:

FIG. 1 is a schematic side elevational view of an apparatus embodying one form of my invention, the apparatus comprising a vertically reciprocable loading platform for three stacks of objects and being shown in a position in which its two loading members are about to deposit the bottom object of the central stack;

FIG. 2 is a smaller-scale side elevational view of the apparatus with certain parts omitted and showing the loading members in two additional positions with respect to the loading platform in which the loading members deposit objects in the two outer stacks at the opposite sides of the central stack;

FIG. 3 is a side elevational view of a fully loaded platform showing three equally high stacks of objects and two additional objects placed in staggered relation on top of the stacks to retain the latter in the illustrated position;

FIG. 4 is a side elevational view of a slight modification showing the loading members in a median position for depositing an object in the central stack, and in two additional positions in which the loading members deposit objects in slightly inclined position with respect to the central stack;

FIG. 5 is a side elevational view of a platform with three stacks of objects formed by the modified apparatus of FIG. 4, further showing two additional objects placed in staggered relation at the top of the stacks;

FIG. 6 is an enlarged schematic side elevational view of a further modification which utilizes three loading members, the reciprocable platform and the discharge conveyor having been omitted for the sake of clarity;

FIG. 7 is a smaller-scale simplified side elevational view of the apparatus shown in FIG. 6, its central and its left-hand loading members being shown in a position in which they define an upwardly opening compartment containing an object about to be deposited on the two-stack platform therebelow;

FIG. 8 shows the apparatus of FIG. 7 in the next stage of its operation in which its central and its left-hand loading members are about to turn the object from a substantially vertical into a horizontal position;

FIG. 9 shows a further stage of operation during release of an object onto the left-hand portion of the platform;

FIG. 10 shows the apparatus of FIGS. 6-9 in a position similar to the position of FIG. 9 in which the central and the right-hand loading members define a second compartment containing an object intended for deposition on the right-hand portion of the platform;

FIG. 11 shows the next stage of operation in which the central and the right-hand loading members are about to turn the object from a substantially vertical into a horizontal position; and

FIG. 12 illustrates the apparatus in a position in which the object is released by the central and the right-hand loading members and is about to drop by gravity onto the right-hand portion of the loading platform.

Referring now in greater detail to the illustrated embodiments, and first to the embodiment of FIGS. 1 and 2, FIG. 1 shows a portion of a supply conveyor which comprises an endless band or chain 1 and a roller or sprocket 2. The roller 2 rotates in a direction indicated

by the arrow whereby the upper run of the band 1 delivers at spaced intervals certain objects, such as filled sacks or any other type of bulky goods, which the apparatus of FIG. 1 is adapted to arrange in three vertical stacks 5 on the object receiving means here shown as a platform 20.

Beneath the discharge end of the supply conveyor, i.e. substantially below but slightly to the right of the roller 2, there is provided a pair of novel loading members each 10 of which is articulately mounted in a swingable supporting frame 18. The left-hand loading member L_a comprises a plate-like main body portion 3 whose horizontal upper edge is swingable about a horizontal shaft 7 mounted in the frame 18, and short retaining means 5 which extends in a direction to the right from and is fixed in the proximity of the lower end, preferably directly to the horizontal lower edge of the plate 3. The connection 5a between the plate 3 and strip-shaped retaining means or extension 5 is preferably of the adjustable type, i.e. 15 the angle between these parts may be varied as desired to fix the retaining means 5 in a requisite position with respect to the main body portion or plate 3. The construction of the right-hand loading member L_b is similar, i.e. it comprises a plate-like main body portion 4 and strip-shaped retaining means or extension 6 which latter 20 extends to the left, that is, toward the body portion of the loading member L_b , and is adjustably fixed to the lower end portion, preferably directly to the lower horizontal edge of the plate 4 by a schematically represented 25 mechanism 6a. However, while the shaft 7 is connected with or rather close to the upper edge of the plate 3, i.e. at a considerable distance from and above the lower edge of member 3, the plate 4 of the second or right-hand loading member L_b is pivotable about a horizontal shaft 8 which is closer to the lower than to the upper end of the plate 4. Shaft 8 is also mounted in the frame 18. It 30 will be noted that the shafts 7, 8 are perpendicular to the direction in which the objects are advanced by the supply conveyor 1, 2.

40 The plates 3, 4 are articulately connected to each other by means of a connecting rod 9, the connection 9a between the rod 9 and plate 3 being located below the shaft 7, i.e. closer to the lower edge of the plate 3, and the connection 9b between the parts 4, 9 being located 45 above the right-hand shaft 8, i.e. more distant from the lower edge of the plate 4. Such mode of connection between the rod 9 and plates 3, 4 brings about angular movements of the plates in opposite directions, i.e. if the loading member L_a is swung clockwise about the shaft 7, the other loading member necessarily pivots in 50 anticlockwise direction about the shaft 8, and vice versa. The length of the connecting rod 9 is preferably adjustable which enables an operator to change the volume of the upwardly opening compartment or space C which 55 is defined by the parts 3-6 in the full-line position of FIG. 1. For example, the connecting rod 9 may consist of two telescoped sections 9', 9'' which are releasably fixed to each other by a screw bolt 9c or by any other suitable locking means. By changing the effective length 60 of the rod 9 between the connections 9a and 9b, an operator may change the volume of the compartment C in order to accommodate bulkier or smaller objects, or to accommodate objects whose configuration is out of normal, e.g. slightly or pronouncedly trapezoidal or even 65 triangular pieces of goods.

The means for pivoting the loading members L_a , L_b about their shafts 7, 8, respectively, in addition to the rod 9, comprises a double-acting cylinder and piston assembly 10, 10a, and a piston rod 12 which is articulately fixed to the plate 4 by a pivot pin 12a located 70 between the shaft 8 and the point of connection 9b. The left-hand end of the cylinder 10 carries a bracket or eye 11 which is pivotable about a horizontal pin 11a fixed to the frame 18 whereby the cylinder 10 and the piston rod 12 may pivot in a vertical plane to follow 75

the angular movements of the plate 4 about its shaft 8. The piston 10a is reciprocable by a gaseous or liquid pressure medium (e.g. compressed air or oil) which is alternately introduced through the preferably flexible conduits 13a, 13b both leading to a distributor valve 13 which latter receives fluid through a supply conduit 14. The conduit 14 receives fluid from a source 14a (here shown as an oil tank) through a pressure generating device such as a gear pump 14b or the like. The valve 13 is also connected with a discharge conduit 14c which leads back to the source 14a and which may communicate with the conduits 13a, 13b and 14, depending upon whether the piston 10a is to move to the right or to the left, or whether the line 14c merely returns the fluid delivered by the pressure generating device 14b. The valve 13 is preferably a three-way magnet valve and receives impulses from a schematically indicated control device 16 through a conductor or connecting means 15. The control device 16, in turn, receives impulses from and is operated by a photoelectric cell 17 which is adjacent to one side of the endless band 1 at the latter's upper run and cooperates with a light source 17a to send operating impulses to the control device 16, to the magnet valve 13 and to the parts 9-12 of the pivoting means whenever an object advancing along the upper run of the supply conveyor interrupts the light beam passing from the light source 17a to the cell 17. Thus, the pivotal movements of the loading members L_a, L_b are triggered or initiated by the objects while the objects move along and toward the discharge end of the supply conveyor.

The frame 18 is articulately connected with the upper ends of elongated supporting members or uprights 19 whose lower ends are pivotally connected to the ground, as at 19a. The apparatus may comprise two or more pairs or uprights 19 and eventually two supporting frames 18, one at each end of the shafts 7, 8, with the loading members L_a, L_b located between the two frames. The uprights 19 constitute a supporting parallelogram which is adapted to cause the frame means 18 and the loaders L_a, L_b to perform swinging movements in a vertical plane to the opposite sides of the central position which is shown in FIG. 1, i.e. the frame means and the uprights are movable into the positions 18_{II}, 19_{II}, and 18_{III}, 19_{III} which are indicated in FIG. 2. Of course, the frame means 18 may assume a number of additional positions between the positions 18_{II} and 18_{III}; the purpose of such additional intermediate positions other than the central position of FIG. 1 will be described in full detail in connection with FIG. 3.

The means for swinging the upright supporting members 19 about their ground connections 19a comprises an arrangement which is schematically indicated by the phantom line 16a and which preferably receives operating impulses from the control device 16. The exact construction of this swinging means 16a forms no part of the present invention.

The operation of the stacking or loading apparatus is as follows:

When the light beam between the source 17a and the photoelectric cell 17 is interrupted by a, say, substantially flat rectangular sack which travels to the right along the upper run of the conveyor band 1, the control device 16 receives an operating impulse from the cell 17 and adjusts the valve 13 to a position in which the conduit 13a delivers pressure fluid to the left-hand side of the piston 10a whereby the piston and its rod 12 move in a direction to the right. The rod 12 pivots the loading member L_b in clockwise direction while the connecting rod 9 simultaneously brings about an anticlockwise pivotal movement of the other loading member L_a. The loading members L_a, L_b then assume the full-line positions of FIG. 1 in which the extension or retaining means 6 overlaps the extension or retaining means 5 and in which the compartment C assumes the form of an upwardly and

outwardly tapering trapezoidal space whose upper end is open and is located in the path of the object advancing toward and about to drop over the sprocket or roller 2. Alternately, the operation of the control device 16 may be such that it automatically returns the loading members L_a, L_b into the full-line positions of FIG. 1 whenever a stacking step is completed, i.e. after each release of an object by the loading members.

After a given period of time which may be determined by a time-lag relay or the like forming part of the control device 16, the latter causes the valve 13 to deliver fluid through the conduit 13b and to permit discharge of fluid through the conduit 13a whereby the piston 10a moves its rod 12 in a direction to the left and the loading members L_a, L_b assume their phantom-line positions L_a', L_b', respectively (FIG. 1). In other words, the loading member L_b pivots anticlockwise while the loading member L_a performs a clockwise pivotal movement and the retaining means 5, 6 move away from each other. In their positions L_a', L_b', respectively, the two loading members transform the upwardly opening compartment C into a trapezoidal compartment C' (indicated in FIG. 2 for the sake of clarity) whose underside is open to permit discharge of an object onto the vertically reciprocable receiving means or platform 20. It will be noted that, when the loading members L_a, L_b assume the positions L_a', L_b', respectively, the distance between the retaining means 5, 6 is greater than the maximum dimension of an object, e.g. a sack 23, which was delivered into the upwardly opening compartment C in the preceding step of the stacking operation.

The compartment C is preferably of such shape that it holds a sack 23 in a substantially vertical plane and in such a way that the underside of the sack (i.e. that side which was in contact with the upper run of the conveyor band 1) rests against the inner or righthand side of the plate 3 while a narrow end face or the horizontal bottom edge of the sack 23 rests on the overlapping retaining means 6. The normally upper side of the sack 23 faces the inner or left-hand side of the plate 4 when the sack drops into the compartment C. When the loading members L_a, L_b pivot toward their second extreme positions L_a', L_b', respectively, the underside of the sack 23 slides along the inner side of the plate 3 while the retaining means 6 holds the longitudinal lower edge or end face of the sack until the latter reaches the phantom-line position 24 which is shown in FIG. 1. The sack is then free to drop onto the upper side of the platform 20 and assumes the phantom-line position 25 at the center of the platform. Thus, when the sack is advanced from the upper run of the band 1 into the upwardly opening first compartment C, thereupon into the downwardly opening second compartment C' (position 24) and finally into the position 25, its side which was in contact with the band 2 again becomes its underside by coming to rest on the upper side of the object receiving platform 20. In the position 25, the sack constitutes the bottom object of the central stack Y on the loading platform 20 (see FIG. 3). As stated hereinabove, as soon as the sack is released from the inverted or downwardly opening second compartment C', the loading members preferably automatically return into their full-line positions L_a, L_b of FIG. 1 in which they again form an open-top or upwardly opening compartment C to receive a second object.

The frame swinging means 16a, 19 preferably operates in such a way that each second impulse conveyed by the photoelectric cell 17 to the control device 16 brings about a swinging movement of uprights 19 into the position 19_{II} of FIG. 2, and that each third impulse received by the control device 16 causes the uprights to move into the position 19_{III}. When the uprights assume the position 19_{II}, the frame 18 is advanced into the position 18_{II} and moves the loading members, which latter already hold an object 24_{II}, into a position above the left-hand portion of the object receiving platform 20. Thus, when the

retaining means 5, 6 release the object 24_{II}, the latter assumes the position 26 and forms the bottom object of the left-hand stack X to be formed on the platform 20. The object 24_{III} held by the loading members in the frame position 18_{III} ultimately forms the bottom object 27 of the right-hand stack Z.

By cyclically repeating the movements of the uprights 19 into the position of FIG. 1 and thereupon into the positions 19_{II}, 19_{III} of FIG. 2, the photoelectric means 17, 17a, the control device 16, and the frame swinging operative connection 16a cause the loading members to build up three stacks X, Y, Z (FIG. 3) of equal height. The platform 20 is reciprocable upwardly toward and downwardly away from the frame means 18 and retaining means 5, 6 by schematically indicated carriers 21. The arrangement is such that the carriers 21 lift an empty platform 20 all the way up and closely beneath the retaining means 5, 6 of the loading members L_a, L_b (see FIGS. 1 and 2), whereupon the platform descends to an extent preferably corresponding to the thickness of an object whenever a full horizontal layer or row of objects has been deposited thereon, i.e. whenever the uprights complete a full cycle of movements into the position of FIG. 1 and into the positions 19_{II}, 19_{III} of FIG. 2 to uniformly build up the stacks X, Y, Z by adding to each of these stacks a single object in a predetermined sequence. It will be readily understood that the sequence in which the objects are deposited on the platform 20 may be varied at will, i.e. that say the bottom object 25 may be deposited before the bottom object 26, that the bottom object 27 may be deposited first, and so forth. It is preferred to deposit an object in the central stack Y before depositing objects in the stacks X and Z.

The means for causing intermittent movements of the carriers or supporting means 21 and of the object receiving platform 20 in downward direction may comprise a weight-responsive device which causes the platform and the carriers to descend whenever the weight of the platform increases by the combined weight of three objects or, alternately, it may comprise a device which is responsive to increases in the height of a stack on the platform 20, i.e. which is tripped whenever the last of three successive objects (e.g. the sack 27) drops from the downwardly opening second compartment C' onto the platform. A fully loaded platform (see FIG. 3) descends all the way onto the supporting surface of a schematically indicated discharge conveyor 22 and is transported into storage or to any other destination.

Referring back to FIG. 1, it will be noted that, when the loading members L_a, L_b assume their phantomline positions L_{a'}, L_{b'}, respectively, their retaining means 5, 6 are simultaneously removed from the underside of the sack 24. This is due to the fact that, while sliding along the inner side of the plate 3, the sack 23 is caused to slide with its lower end face further toward the plate 4 just above the retaining means 6 so that, in an intermediate stage of movement toward the positions L_{a'}, L_{b'}, the two end faces of the sack 23 which are perpendicular to the plane of FIG. 1 come into full or near abutment with the plates 3 and 4. In the last stage of movement by members L_a, L_b into the positions L_{a'}, L_{b'}, respectively, the retaining means are caused to move simultaneously away from the underside of the sack which latter is already in the horizontal position 24 so that the sack is simultaneously released by said retaining means and may drop onto the platform 20 while remaining in a substantially horizontal plane. The procedure is identical when the sack 24_{II} is caused to drop into the position 26, and also when the sack 24_{III} drops into the position 27 (see FIG. 2), i.e. when the frame means 18 is in the positions 18_{II}, 18_{III}, respectively.

FIG. 3 illustrates a pair of sacks 60, 61 which are placed above and in staggered relation between the uppermost sacks 26_u, 25_u and 25_u, 27_u, respectively. The sack 60 prevents eventual collapsing of the stack X in a direc-

tion to the left and away from the central stack Y, and the right-hand sack 61 holds the stack Z against movement away from the stack Y. As mentioned hereinabove, the frame 18 may be caused by the swinging means 16a, 19 to assume one or more intermediate positions between the additional or extreme positions 18_{II}, 18_{III}, said intermediate positions being other than the central position of FIG. 1. In one of such additional positions (i.e. when the frame is between the position 18_{II} and the position of FIG. 1), the loaders L_a, L_b deposit the sack 60. The other uppermost sack 61 is deposited when the frame assumes a position between the position 18_{III} and the central position of FIG. 1. The movement of the frame into such intermediate positions may be fully automatic and may be triggered by the uppermost sack in one of the stacks X, Y, Z.

It has been found that the placing of two objects in staggered relation above and between the uppermost objects in three adjacent stacks is not always sufficient to prevent a collapse of the stacks during transportation of the platform 20. This can be corrected by stacking the goods, e.g. filled sacks or the like, in a manner as shown in FIG. 5 which indicates that the sacks in the two outer stacks X_a, Z_a are inclined in opposite directions with respect to the horizontal sacks in the central stack Y_a. In other words, the general plane of each object in the outer stacks X_a, Z_a encloses an acute angle with and in a direction outwardly and away from the general planes of objects in the central stack Y_a. This is also known as stacking at a slant. The purpose of the two uppermost objects 60_a, 61_a is the same as that of the objects 60, 61 on the stacks of FIG. 3.

The apparatus for stacking the objects in the manner of FIG. 5 is illustrated in FIG. 4. The uprights 59 which support the frame 18 and the loaders L_a, L_b are not parallel as the uprights 19 of FIG. 1 but enclose with each other an acute angle, i.e. their upper ends converge toward each other. Consequently, when the uprights 59 are in their full-line central positions, the loaders may deposit an object 62 in horizontal position. However, when the uprights assume the left-hand phantom-line positions 59_{II}, the frame in the position 18_{II} is inclined and causes the loaders L_a, L_b (shown in the positions L_{a'}, L_{b'}) to drop the object 63 at a slant as is shown in FIG. 5. Analogously, when in the position 59_{III}, the uprights maintain the frame in the inclined position 18_{III} and cause the loaders to deposit the object 64 at an angle with respect to the central object 62, the position of objects 63, 64 being in mirror reverse with respect to a vertical plane passing through the center of the object 62. It can be said that the conveyor 22, the uprights 59, and the frame 18 in FIG. 5 form the sides of a trapezoid with two parallel horizontal sides and two inclined sides (59). When the uprights move into the positions 59_{II} and 59_{III}, the entire arrangement assumes the form of a trapezium as is clearly shown in phantom lines. It will be noted that, when the frame 18 is in the additional position 18_{II} or 18_{III} (i.e. in a position other than the central position 18 of FIG. 4), the retaining means closer to the central stack Y_a is at a level lower than the other retaining means. Thus, when the frame is in the position 18_{II} of FIG. 4, the retaining means 6 is at a lower level than the retaining means 5.

It will be readily understood that, if desired, the objects 65 may be stacked in inverted position. All that is necessary is to mount the retaining means 5, 6 in such a way that the former overlaps the latter, i.e. that the bottom end face of the object 23 shown in FIG. 1 comes to rest upon the retaining means 5. While moving into the position L_{a'}, the left-hand loading member L_a then causes the object 23 to slide along the left-hand side of the plate 4 and to become inverted at the time it reaches the position 24. Such arrangement may become desirable when the upper sides of objects traveling on the endless band 1 70 receive a first set of impressions, such as lettering, nu-

merals or the like, and the other sides of objects should also receive matter immediately after deposition on the platform 20. For example, if the right-hand side of the sack 23 shown in FIG. 1 is already provided with printed matter, and assuming that the retaining means 5 overlaps the retaining means 6, the lower end of the sack will follow the movement of retaining means 5 into the phantom-line position and, consequently, that which originally was the underside becomes the upper side of the sack when the latter assumes the position 24. After the sack drops into the position 25, printed matter may be applied to its upper side before the next sack is stacked in the row Y.

In order to allow for removal of a loaded platform 20 by the discharge conveyor 22 and in order to allow for the movement of an empty platform into the position of FIG. 1, the fully loaded platform 20 in its lowermost position may trigger a device which automatically arrests the supply conveyor 1, 2 to thereby inactivate the loading members L_A, L_B because the light beam between the source 17a and the cell 17 remains uninterrupted. Also, the double-acting cylinder and piston assembly 10, 10a may be replaced by an electric motor and by a suitable linkage or other purely mechanical connection adapted to pivot the loading members L_A, L_B into and between their extreme positions.

The stacking apparatus may operate with a single retaining means 5 or 6, if desired. Thus, by omitting the retaining means 5 (FIG. 1), and by eventually shortening the retaining means 6, the apparatus may still discharge an object in horizontal or substantially horizontal position, but it is preferred to utilize a pair of cooperating retaining means because they can positively hold the underside of an object in the latter's horizontal position up to the exact time of discharge from the downwardly opening compartment C'.

Referring now to FIG. 6, there is shown a slightly modified stacking or loading apparatus which differs from the apparatus of FIGS. 1 and 4 in that it comprises a stationary frame 65 and in that it utilizes three loading members which are adapted to deposit the objects in two adjacent stacks without requiring any swinging movements of the frame. The frame 65 mounts three spaced parallel horizontal shafts 49, 50, 51 for the loading members L_A, L_B, L_C, respectively. The shafts 49 and 51 are fixed to the upper horizontal edges of plate-like main body portions 28, 30 forming part of the two outer loading members L_A, L_C, respectively. The shaft 50 is connected with the plate-like main body portion 29 of the central loading member L_B at a point below the latter's central portion. The connection between the loading members L_A, L_B comprises a connecting rod 35 which is articulately fixed to the plates 28, 29 at 35a, 35b, respectively. The length of this rod 35 is adjustable in a manner not shown in the drawings, e.g. in the same way as illustrated in FIG. 1 in connection with the rod 9. The connection between the loading members L_B, L_C comprises a second longitudinally adjustable rod 36 which is articulately fixed to the plates 29, 30 at 35b, 36c, respectively. The point of connection 35b between the rods 35, 36 and the plate 29 is located above the central shaft 50. The point 35a is located between the shaft 49 and the lower edge of plate 28, and the point 36c is located between the shaft 51 and the lower edge of plate 30.

The lower horizontal edges of outer plates 28, 30 are articulately connected with retaining means 34, 31 by suitable connections 34a, 31a, respectively, i.e. the angles formed between the plate 28 and retaining means 34 on the one hand, and between the plate 30 and the retaining means 31 on the other hand are adjustable within a wide range. The lower horizontal edge of central plate 29 is adjustably connected with a pair of oppositely inclined retaining means 32, 33 with the help of a suitable connecting device 32a. The outer retaining means 31, 34 are normally turned toward the adjacent sides of the central

5 10 15 20 25 30 35 40 45 50 55 60 65 70 75

plate 29; the left-hand retaining means 33 of the loader L_B is normally at least slightly inclined toward the right-hand side of the outer plate 28; and the right-hand retaining means 32 of the loader L_B is normally somewhat inclined toward the left-hand side of the plate 30.

In the position of FIG. 6, the loading members L_A and L_B define an upwardly expanding substantially trapezoidal first compartment C₁ whose upper end is open to receive an object 46 and whose lower end is closed by the retaining means 33, 34 so that the lower end face of the object 46 rests on the overlapping retaining means 33. At the same time, the loading members L_B, L_C define a downwardly expanding trapezoidal compartment C₂ whose lower side is open sufficiently to permit automatic discharge of another object (see the sack 47 in FIG. 12). The distance between the retaining means 31, 32 in the position of FIG. 6 is greater than the maximum dimension of an object, i.e. those retaining means cannot impede a gravitational descent of objects from the compartment C₂. The means for pivoting the loading members L_A, L_B, L_C about the shafts 49, 50, 51 respectively, in addition to the rods 35 and 36, comprises a double-acting cylinder 38 whose left-hand end carries a bracket or eye 37 articulately fixed to the stationary frame 65 by a horizontal pin 37a. The cylinder 38 receives a reciprocable piston 38a whose piston rod 39 is articulately fixed to the lower end of a link or crank 40, the latter being fixed to and being swingable with the plate 29 of the central loading member L_B. The connection between the piston rod 39 and the member 40 consists of a horizontal pivot pin 39a. It will be seen that the cylinder 38 is swingable about the pin 37a in a vertical plane when its piston 38a pivots the plate 29 about the shaft 50 whereby the connecting rods 35, 36 simultaneously pivot the outer loading members into the positions L_A', L_C' which are shown in FIGS. 9 and 10. The central loading member L_B then assumes the position L_B', i.e. the loading members transform the upwardly opening compartment C₁ into a downwardly and outwardly expanding and opening left-hand compartment C₁', and simultaneously transform the compartment C₂ into an upwardly and outwardly expanding and opening right-hand compartment C₂'. When in the position of FIG. 9, the retaining means 31 of the right-hand loading member L_C overlaps the retaining means 32 of the central loading member L_B so that an object 47 (FIG. 10) may come to rest upon the retaining means 31 after passing through the open upper end of the compartment C₂'.

The double acting cylinder 38 is operated by a hydraulic or pneumatic fluid (e.g. oil or compressed air) which is alternately introduced through a pair of conduits 41, 42, the conduit 41 delivering fluid when the loading members L_A, L_B, L_C must be moved from the positions of FIG. 6, 7 or 12 into the intermediate positions L_A'', L_B'', L_C'' of FIG. 8 or 11, and finally into the other extreme positions L_A', L_B', L_C' of FIG. 9 or 10. The right-hand conduit 42 delivers fluid to the cylinder 38 when the piston 38a and its rod 39 should pivot the loading members L_A, L_B, L_C from the positions of FIG. 9 through the intermediate positions of FIG. 8 back into the positions of FIGS. 6 and 7. The conduits 41, 42 are connected to a preferably three-way magnet valve 43 which receives fluid from a non-illustrated source through a supply conduit 44. The energizable magnetic circuits of the valve 43 are conductively connected with and receive impulses from a control device 45 which latter, in turn, receives operating impulses from a photoelectric cell 17 which cooperates with a light source 17a to convey impulses to the control device 45 through conductor means 17b whenever an object advancing along the upper run of the supply conveyor 1, 2 interrupts the light beam produced by the source 17a. The cell 17 and the source 17a are located at a predetermined distance from the discharge end of conveyor means 1, 2 so that the double acting cylinder 38 may move the loading members L_A, L_B, L_C into the position of FIG. 7 or 10 before

an object, e.g. a sack 46 or 47, actually reaches and passes over the discharge end of the supply conveyor. Thus, the movements of all three loading members are again triggered by the objects which are to be stacked by the improved apparatus.

While the exact construction of the control device 45 does not form an essential part of my invention because the loading or stacking apparatus may be controlled by many types of presently known devices, I will now shortly describe one preferred form of control means which may operate the piston 38a that actually pivots the loading members L_A, L_B and L_C. Thus the control device may comprise a step-by-step relay having an even number of relay points each corresponding to a switching step. The relay points corresponding to even-numbered operating steps are connected in parallel with each other and are further connected with that energizable magnetic circuit of the magnet valve 43 which controls the flow of compressed fluid to one side of the piston 38a (e.g. the flow of fluid through the conduit 41 toward and into the cylinder 38), as well as with a second energizable circuit of the magnet valve 43 which controls the backflow of fluid from the opposite side of the piston 38a (i.e. the flow of fluid through the conduit 42 back to the magnet valve). The relay points corresponding to oddly numbered operating steps are then connected in parallel with each other as well as with two additional energizable circuits of the magnet valve 43, one of said additional circuits controlling the flow of fluid through the conduit 41 and back to the valve 43, and the other additional circuit controlling the admission of fluid through the conduit 42 toward and into the cylinder 38.

The apparatus of FIG. 6 also comprises a vertically reciprocable platform 66 which is caused to descend, preferably in a fully automatic way in the same manner as described in connection with FIG. 1, whenever it receives two additional objects, i.e. one for each of the two stacks to be formed thereon by the loading members L_A, L_B and L_C. When empty, the platform 66 assumes its uppermost position immediately or closely below the retaining means 31-34, but always at such distance from the loading members that no damage can occur to an object which drops by gravity from the compartment C₁' or C₂. The discharge conveyor, corresponding to the conveyor 22 of FIGS. 1, 2 and 4, whose purpose is to move a fully loaded platform 66 to its destination is not shown in FIGS. 6-12.

The loading or stacking apparatus of FIG. 6 operates as follows:

For the purposes of the description which will be made in connection with FIGS. 7-12, it is now assumed that the control device 45 comprises the aforementioned step-by-step relay. FIG. 7 shows an object, e.g. a sack 46, in the compartment C₁ formed by the left-hand loading member L_A and the central loading member L_B in the position of the apparatus which is the same as shown in FIG. 6. A next sack 47 is about to pass between the photoelectric cell 17 and the light source 17a (not shown in FIG. 7), i.e. the cell 17 is about to convey an operating impulse through the conductor 17b which impulse is released when the light beam passing from the source 17a to the cell 17 is interrupted by the sack 47. As soon as the light beam is interrupted, the step-by-step relay of the control device 45 switches into a next position in which the magnet valve 43 is operated in such a way that it permits the flow of pressure fluid from the conduit 44 into the conduit 41 to thereby advance the piston 38a in a direction to the right. The piston rod 39 and the link 40 then pivot the central plate 29 about the shaft 50 in anticlockwise direction which results in clockwise rotation of plates 28, 30 about the shafts 49, 51, respectively. As explained hereinabove, the valve 43 simultaneously permits return flow of fluid from the right-hand side of the piston 38a, through the line 42, and back into the magnet valve so that the piston meets

no resistance during its travel to right for moving the loading members from the positions L_A, L_B, L_C of FIG. 6 or 7 through the intermediate positions L_A', L_B', L_C' of FIG. 8 into the end positions L_A', L_B', L_C' of FIG. 9.

- 5 The movements of loading members during the advance of piston 38a to right are indicated by small arrows in FIG. 8. During such movements of the loading members, the sack 46 which rests on the overlapping retaining means 33 slides by gravity along the right-hand side 10 of the plate 28 through the position of FIG. 8 into the horizontal position of FIG. 9, and finally drops by gravity onto the left-hand portion of the platform 66 (position 46a) to constitute the bottom object of the left-hand stack to be formed on said platform. By tracing the 15 movements of the sack 46 from the position 46 in FIG. 7 to the final position 46a on the platform 66, it will be readily noted that the underside of said sack (i.e. that side which is in contact with the inner or right-hand side of the left-hand plate 28) comes to rest on the upper side 20 of the loading platform. It can be said that, while the loading members L_A, L_B perform pivotal movements in opposite directions to transform the upwardly opening compartment C₁ into a downwardly opening compartment C₁', the sack 46 pivots from a fully or nearly vertical position (FIGS. 6 and 7) in anticlockwise direction (FIG. 8) into a horizontal or nearly horizontal position of FIG. 9, and finally descends by gravity into the position 46a as soon as its underside is released by the retaining means 33 and 34.
- 30 The movement of loading members L_A, L_B, L_C into the end positions of FIG. 9 and the discharge of sack 46 into the position 46a are completed before the next sack 47 reaches the discharge end of the supply conveyor 1, 2, i.e. the loading members L_B, L_C complete the 35 formation of the upwardly opening pocket or compartment C₂' in good time so that the sack 47 may be received therein in a manner as shown in FIG. 10. The sack 47 comes to rest on the retaining means 31 of the loading member L_C. In the meantime, a next sack 48 is 40 about to interrupt the light beam from the source 17a to the cell 17 so that the latter again sends an impulse through the conductor means 17b whereupon the step-by-step relay of the control device 45 switches into a further position in which the valve 43 permits the flow 45 of fluid from the conduit 44 into the conduit 42 and simultaneously permits return flow of fluid from the left-hand side of the piston 38a and through the conduit 41 back to the valve 43. The piston 38a now moves to left and pivots the loading members through the intermediate positions L_A'', L_B'', L_C'' of FIG. 11 back into the initial positions L_A, L_B, L_C of FIG. 12. The directions in which the main body portions 28, 29, 30 of the loading members are pivoted during an advance of the piston 38a to left are indicated by short arrows in FIG. 50 11. As the loading members L_B, L_C move into and beyond the positions of FIG. 11, the sack 47 which rests on the retaining means 31 is caused by gravity to pivot in anticlockwise direction by sliding along the right-hand side of the plate 29 and finally reaches the full-line horizontal position of FIG. 12 whence it drops by gravity into the position 47a on the upper side of the right-hand portion of platform 66. The position of the apparatus shown in FIG. 12 corresponds to the position of FIG. 7, i.e. the loading members L_A, L_B again define the upwardly opening compartment C₁ ready to receive the next sack 48 which is about to drop over the discharge end of the supply conveyor 1, 2. The cycle is then repeated in that the sack 48 is deposited onto the sack 46 in the latter's 55 position 46a, and the next-following sack 67 is deposited onto the sack 47 in the latter's position 47a, and so forth until the two stacks on the platform 66 reach the desired height. It will be readily understood that the platform 20 or 66 may be replaced by any other suitable type of 60 object receiving means, for example, by a rectangular 65 70 75

receptacle which, when filled, may be immediately sealed and is ready for shipment.

The advantageous feature of the improved apparatus that it may deposit the underside of an object onto the upper side of the platform can be readily traced by following the path of the sack 47 in FIGS. 9 to 12. FIG. 9 shows that the sack 47 is about to drop into the compartment C_2' in such a way that its underside, previously in contact with the upper run of the band 1, comes to rest against the right-hand side of the central plate 29 (FIG. 10). The underside of the sack 47 then slides along the right-hand side of the plate 29 (FIG. 11) and is turned toward the upper side of the platform 66 when the sack 47 reaches the horizontal position of FIG. 12. This becomes important when only the upper sides of the goods are provided with inscriptions, numbers or any other type of indicia because such indicia are again observable when the goods come to rest on the loading platform.

As explained hereinabove, the adjustable connections 34a, 32a, 31a between the retaining means 34, 32—33, 31 and the plates 28, 29, 30, respectively, enable an operator to adjust the apparatus in such manner that the objects are properly supported in the compartments C_1 and C_2' , and also that the objects are released by the respective retaining means in preferably horizontal or nearly horizontal position as was described hereinabove in connection with FIGS. 1 and 4. In addition, such adjustments of the retaining means, coupled with longitudinal adjustability of connecting rods 35 and 36, enable the operator to readily adapt the volume and shape of compartments C_1 and C_2' for reception of objects of greatly differing dimensions and configuration, i.e. the improved loading apparatus is one of nearly universal utility in that it can be used in connection with smaller, larger, lighter, heavier, and differently configurated types of goods.

It will be readily understood that, in its simplified form, the apparatus may be utilized for stacking objects in a single row; such apparatus merely comprises a stationary frame and a pair of loading members.

Without further analysis, the foregoing will so fully reveal the gist of the present invention that others can, by applying current knowledge, readily adapt it for various applications without omitting features that, from the standpoint of prior art, fairly constitute essential characteristics of the generic and specific aspects of this invention and, therefore, such adaptations should and are intended to be comprehended within the meaning and range of equivalence of the following claims.

What is claimed as new and desired to be secured by Letters Patent is:

1. An apparatus for the deposition of objects in at least one stack which comprises, in combination, a frame; a pair of spaced substantially horizontal shafts mounted in said frame; two loading members, each comprising a main body portion having a lower end and substantially horizontal retaining means connected with and located in the proximity of the lower end of the respective body portion, said retaining means inclined toward each other and each body portion pivotally mounted on one of said shafts at a point spaced from the lower end thereof; and means operatively connected with said body portions for pivoting the same about the respective shafts into a first position in which the retaining means overlap and said members define an upwardly opening compartment for reception of an object from above and the object comes to rest on the one retaining means which overlaps the other retaining means, and into a second position in which said members transform said compartment into a downwardly opening second compartment and the retaining means are moved away from each other whereby the object is first tilted so that a portion thereof comes to rest on the other retaining means, and the object is thereupon released and drops from the second compartment

when the body portions continue to pivot toward said second position.

2. An apparatus for the deposition of objects in at least one stack which comprises, in combination, supply conveyor means for moving a series of objects at spaced intervals, said conveyor means having a discharge end over which the objects may drop; a pair of substantially horizontal shafts disposed beneath the discharge end of and perpendicular to the direction in which the objects are moved by said conveyor means; two loading members, each comprising a main body portion formed with a substantially horizontal lower edge and retaining means connected to said edge and inclined toward the body portion of the other member, each body portion pivotally mounted on one of said shafts at a point spaced from the lower edge thereof; means operatively connected with said loading members for pivoting the same about the respective shafts in opposite directions into a first position in which the retaining means overlap and said members define an upwardly opening compartment for reception of an object dropping over the discharge end of said conveyor means whereby the object comes to rest on the one retaining means which overlaps the other retaining means, and again in opposite directions into a second position in which said members transform the compartment into a downwardly opening second compartment and the retaining means are moved away from each other sufficiently to permit discharge of the object by gravity from said second compartment; and control means for operating said pivoting means, said control means comprising means for conveying operating impulses to said pivoting means in response to movements of objects on said conveyor means and adapted to operate said pivoting means in such manner and at such intervals that said members define the upwardly opening compartment whenever an object drops over the discharge end of said conveyor means.

3. An apparatus for the deposition of objects in at least one stack which comprises, in combination, supply conveyor means for supporting the undersides of and for moving a series of objects at spaced intervals, said conveyor means having a discharge end over which the objects may drop; a pair of substantially horizontal shafts disposed beneath the discharge end of and perpendicular to the direction in which the objects are moved by said conveyor means; two loading members, each comprising a substantially plate-like main body portion formed with a substantially horizontal lower edge and retaining means connected to said edge and inclined toward the body portion of the other member, each body portion pivotally mounted on one of said shafts at a point upwardly spaced from the lower edge thereof; means operatively connected with said loading members for pivoting the same about the respective shafts in opposite directions into a first position in which the retaining means overlap and said members define an upwardly opening compartment for reception of an object dropping over the discharge end of said conveyor means whereby the object comes to rest on the one retaining means which overlaps the other retaining means and the underside of the object comes to rest against the body portion of that loading member whose retaining means is overlapped, and again in opposite directions into a second position in which said members transform said compartment into a downwardly opening second compartment and the retaining means are moved away from each other sufficiently to permit the discharge of the object by gravity from said second compartment, the underside of the object sliding along said last mentioned body portion and coming to rest on said other retaining means shortly before said loading members reach said second position; and control means for operating said pivoting means, said control means comprising means for conveying operating impulses to said pivoting means in response to movements of objects on said conveyor means and adapted to operate said pivoting means at such intervals that said loading members define the upwardly opening

compartment whenever an object drops over the discharge end of said conveyor means.

4. An apparatus for the deposition of objects in at least one stack which comprises, in combination, a first and a second loading member each comprising a main body portion having a substantially horizontal lower edge and retaining means connected with said lower edge and inclined toward the body portion of the other loading member; a first substantially horizontal shaft pivotally mounting the body portion of the first loading member at a point spaced from the lower edge thereof; a second shaft spaced from and substantially parallel with said first shaft, said second shaft pivotally mounting the body portion of the second loading member at a point spaced from the lower edge thereof, the distance between the first shaft and the retaining means of the first loading member being greater than the distance between the second shaft and the retaining means of the second loading member; and means operatively connected with said body portions for pivoting the same about the respective shafts into a first position in which the retaining means overlap and said loading members define an upwardly opening compartment for reception of an object whereby the object comes to rest on the one retaining means which overlaps the other retaining means, and into a second position in which said loading members transform said compartment into a downwardly opening second compartment and the retaining means are moved away from each other whereby the object is released and drops from the second compartment, said pivoting means comprising connecting means articulately connected to the body portion of the first loading member at a point intermediate said first shaft and the retaining means of said first loading member, and said connecting means further articulately connected to the body portion of the second loading member at a point more distant from the lower edge thereof than said second shaft whereby the body portion of the first loading member always pivots in clockwise direction when the body portion of the second loading member pivots in anticlockwise direction, and vice versa.

5. An apparatus for the deposition of objects in a plurality of stacks comprising, in combination, supply conveyor means for moving a series of objects at spaced intervals, said conveyor means having a discharge end over which the objects may drop; frame means; two spaced substantially horizontal shafts mounted in said frame means and substantially perpendicular to the direction in which the objects are moved by said conveyor means; two loading members each comprising a main body portion formed with a substantially horizontal lower edge and retaining means connected to said edge and inclined toward the body portion of the other loading member, each body portion pivotally mounted on one of said shafts at a point spaced from the lower edge thereof; means for swinging said frame means between a central position in which said loading members are disposed substantially beneath the discharge end of said conveyor means and at least one additional position; means operatively connected with said loading members for pivoting the same—when the frame means is in said central position—into a first position in which the retaining means overlap and said loading members define an upwardly opening first compartment for reception of an object dropping over the discharge end of said conveyor means whereby the object comes to rest on the one retaining means which overlaps the other retaining means, and into a second position in which said loading members transform the first compartment into a downwardly opening second compartment and the retaining means are moved away from each other sufficiently to permit discharge of the object from said second compartment; object receiving means disposed below said retaining means in each position of said frame means; control means for operating said pivoting means, said control

means comprising means for conveying operating impulses to said pivoting means in response to movements of objects on said conveyor means and adapted to operate said pivoting means at such intervals that said loading members define a first compartment whenever an object drops over the discharge end of said conveyor means; and an operative connection between said control means and said swinging means for operating the latter in such manner that said frame means is maintained in said central position when a first object is received in the first compartment for a period of time required by said loading members to transform the first compartment into said second compartment and to deposit the first object in a first stack on said object receiving means, and that said frame means is sequentially swung into each said additional position when subsequent objects are received in the first compartment and before the loading members transform the first compartment into said second compartment whereby the successive objects are deposited in additional stacks on said object receiving means, the number of additional stacks corresponding to the number of additional positions of said frame means.

6. An apparatus for the deposition of objects in two stacks comprising, in combination, a frame; a first shaft, a central second shaft, and a third shaft mounted in said frame, said shafts substantially horizontal and substantially parallel with each other; a first loading member, a central second loading member, and a third loading member, each loading member comprising a main body portion having a substantially horizontal lower edge, the body portions of said first, central and third loading members pivotally mounted on said first, central and third shafts, respectively, said first loading member further comprising first retaining means connected to the lower edge of its body portion and inclined toward the body portion of the central loading member, said central loading member further comprising second and third retaining means both connected to the lower edge of its body portion and inclined toward the body portions of the first and third loading members, respectively, and the third loading member further comprising fourth retaining means connected to the lower edge of its body portion and inclined toward the body portion of said central loading member; and means operatively connected with said loading members for pivoting the same into a first position in which the first and second retaining means overlap, in which the first and central loading members define an upwardly opening first compartment for reception of a first object whereby the first object comes to rest upon that one of said first and second retaining means which overlaps the other of said last mentioned retaining means, in which the third and fourth retaining means are moved away from each other a distance greater than the maximum dimension of an object, and in which said central and third loading members define a downwardly opening second compartment, and into a second position in which the first and central loading members transform the first compartment into a downwardly opening third compartment, in which the first and second retaining means are moved away from each other a distance greater than the maximum dimension of the first object whereby the first object may drop by gravity from said third compartment, in which said third and fourth retaining means overlap, and in which said central and said third loading members transform the second compartment into an upwardly opening fourth compartment for reception of a second object whereby the second object comes to rest on that one of said third and fourth retaining means which overlaps the other of said last mentioned retaining means.

7. An apparatus for the deposition of objects in two stacks comprising, in combination, supply conveyor means for moving a series of objects at spaced intervals, said conveyor means having a discharge end over which the objects may drop; a stationary frame; a first shaft, a central second shaft, and a third shaft, said shafts mounted in

said frame substantially below the discharge end of said conveyor means, said shafts substantially horizontal and each substantially perpendicular to the direction in which the objects are moved on said conveyor means; a first loading member, a central second loading member, and a third loading member, each loading member comprising a main body portion having a substantially horizontal lower edge, the body portions of said first, central and third loading members pivotally mounted on said first, central and third shafts, respectively, said first loading member further comprising first retaining means connected to the lower edge of its body portion and inclined toward the body portion of the central loading member, said central loading member further comprising second and third retaining means connected to the lower edge of its body portion and inclined toward the body portions of said first and third loading members, respectively, and the third loading member further comprising fourth retaining means connected to the lower edge of its body portion and inclined toward the body portion of the central loading member; means operatively connected with said loading members for pivoting the same into a first position in which the first and second retaining means overlap, in which the first and central loading members define an upwardly opening first compartment for reception of a first object dropping over the discharge end of said conveyor means whereby the first object comes to rest on that one of said first and second retaining means which overlaps the other of said last mentioned retaining means, in which the third and fourth retaining means are moved away from each other a distance greater than the maximum dimension of an object, and in which said central and third loading members define a downwardly opening second compartment, and into a second position in which the first and central loading members transform the first compartment into a downwardly opening third compartment, in which the first and second retaining means are moved away from each other a distance greater than the maximum dimension of the first object whereby the first object may drop by gravity from said third compartment, in which said third and fourth retaining means overlap, and in which said central and said third loading members transform the second compartment into an upwardly opening fourth compartment for reception of a second object dropping over the discharge end of said conveyor means whereby the second object comes to rest on that one of said third and fourth retaining means which overlaps the other of said last mentioned retaining means; and control means for operating said pivoting means in such manner that the loading members are alternately moved into said first and second positions, said control means comprising means for conveying operating impulses to said pivoting means in response to movements of objects on said conveyor means and adapted to operate said pivoting means at such intervals that said loading members alternately define said first and fourth compartments whenever an object drops over the discharge end of said conveyor means.

8. An apparatus as set forth in claim 2, wherein said control means comprises means for automatically transforming the upwardly opening compartment into said second compartment when an object is received in said first compartment.

9. An apparatus as set forth in claim 1, wherein each of said body portions comprises a substantially horizontal lower edge and further comprising means for angularly adjustably fixing said retaining means to the lower edges of the respective body portions whereby the extent to which said body portions must be pivoted from said first to said second position to release an object may be varied in response to angular adjustment of said retaining means.

10. An apparatus as set forth in claim 4, wherein said connecting means is a rod-shaped connecting member of adjustable length.

11. An apparatus as set forth in claim 2, further comprising object receiving means disposed beneath said second compartment for receiving in the form of at least one stack the objects discharged from the second compartment, and carrier means for reciprocating said object receiving means toward and away from said retaining means.

12. An apparatus as set forth in claim 11, wherein said carrier means maintains the object receiving means in close proximity of said retaining means when the object receiving means is empty, and further comprising means responsive to increases in the height of a stack on said object receiving means for moving the carrier means and the object receiving means away from the retaining means.

13. An apparatus as set forth in claim 11, wherein said carrier means maintains the object receiving means in close proximity of said retaining means when the object receiving means is empty, and further comprising means responsive to increases in weight of said object receiving means for intermittently moving said carrier means and said object receiving means away from said retaining means.

14. An apparatus as set forth in claim 11, wherein said carrier means maintains the object receiving means in close proximity of said retaining means when the object receiving means is empty, and further comprising operating means for said carrier means, said operating means actuatable by the uppermost object in a stack on said object receiving means for moving the carrier means and the object receiving means away from said retaining means in response to increases in height of a stack on said object receiving means.

15. An apparatus as set forth in claim 5, wherein the frame means is swingable in a vertical plane and the swinging means for said frame means comprises at least one pair of uprights.

16. An apparatus for the deposition of substantially flat objects as set forth in claim 5, wherein the spacing between the retaining means in the second position of said loading members is such that the objects are discharged from the second compartment in substantially horizontal position when the frame means is in said central position, and that the objects are discharged from the second compartment in slightly inclined position when the frame means is in said additional position.

17. An apparatus as set forth in claim 5, wherein the retaining means closer to said first stack is at a level lower than the level of the other retaining means when the loading members transform the first compartment into said second compartment and the frame means is in a position other than said central position.

18. An apparatus as set forth in claim 5, wherein the means for swinging said frame means comprises first and second upright means each having a lower end articulately connected to the ground and an upper end articulately connected with said frame means, said upright means converging toward each other in a direction from the lower toward the upper ends thereof and constituting the sides of a trapezoid when the frame means is in said central position whereby the frame means is inclined with respect to said central position when swung by said upright means into the additional position, said means for pivoting the loading members being mounted on and swingable with said frame means.

19. An apparatus as set forth in claim 5, wherein the frame means is movable by said swinging means into at least one intermediate position between said central position and said additional position, said operative connection between the control means and the swinging means being such that the swinging means moves the frame means into said intermediate position when the first stack and the additional stack reach a predetermined height whereby the loading members deposit an object in stag-

gered relation above and between the central stack and the additional stack.

20. An apparatus as set forth in claim 6, wherein said pivoting means alternately pivots said loading members into said first position by rotating said first and third loading members in one direction and by rotating said central loading member in another direction, and into said second position by rotating the first and third loading members in said other direction and by rotating the central loading member in said one direction.

21. An apparatus as set forth in claim 6, wherein the second retaining means overlaps the first retaining means in the first position of said loading members whereby the first object comes to rest on said second retaining means, and wherein the fourth retaining means overlaps the third retaining means in the second position of said loading members whereby the second object comes to rest on said fourth retaining means.

22. An apparatus as set forth in claim 6, further comprising means for angularly adjustably fixing the first retaining means to the lower edge of the body portion of said first loading member, means for angularly adjustably fixing the second and third retaining means to the lower edge of the body portion of said central loading member, and means for angularly adjustably fixing the fourth retaining means to the lower edge of the body portion of said third loading member.

23. An apparatus as set forth in claim 6, wherein said pivoting means comprises a first connecting member articulately fixed to said first and second loading members for rotating the central loading member in clockwise direction when the first loading member is rotated in anticlockwise direction and vice versa, and a second connecting member articulately fixed to said central and third loading members for rotating the third loading member in clockwise direction when the central loading member is rotated in anticlockwise direction and vice versa.

24. An apparatus as set forth in claim 23, wherein said connecting members are rods of adjustable length and the volumes of said compartments are variable in response to adjustments in the length of said rods.

25. An apparatus as set forth in claim 6, wherein the body portions of said first, central and third loading members are respectively mounted on said first, central and third shafts in such a way that the distance between the central shaft and the lower edge of the body portion of said central loading member is less than the distance between said first and third shaft and the lower edges of the respective body portions of said first and third loading members, the means for pivoting said loading members comprising a first connecting member articulately fixed to said first loading member at a point intermediate said first shaft and said first retaining means and articulately fixed to said central loading member at a point more distant from said second and third retaining means than said central shaft whereby the central loading member is rotated by the first connecting member in clockwise direction when the first loading member rotates in anticlockwise direction and vice versa, and a second connecting member articulately fixed to said third loading member at a point intermediate said third shaft and said fourth retaining means, said second connecting member articulately fixed to said central loading member at a point more distant from said second and third retaining means than said central shaft whereby the third loading member is rotated by the second connecting member in clockwise direction when the central loading member rotates in anticlockwise direction and vice versa.

26. An apparatus as set forth in claim 25, wherein the point of connection between said first connecting member and said central loading member coincides with the point of connection between the second connecting member and said central loading member.

27. An apparatus as set forth in claim 7, wherein the means for conveying operating impulses to said pivoting

means is a photoelectric cell adjacent to the path in which the objects move on and toward the discharge end of said conveyor means.

28. An apparatus as set forth in claim 2, wherein the means for pivoting said loading members comprises double-acting cylinder and piston means, said piston means having a first side and a second side, piston rod means reciprocable by said piston means and articulately connected with one of said loading members, connecting means articulately fixed to both said loading members for rotating one of said loading members in clockwise direction when the other loading member rotates in anticlockwise direction in response to movement of said piston means in one direction and vice versa, a source of pressure fluid, a three-way magnet valve, and conduit means connecting said valve with said source and with said cylinder means at the first and second sides of said piston means, said valve comprising four energizable magnetic circuits the first of which is adapted to admit fluid to the first side of said piston means, the second of which is adapted to permit the flow of fluid from the second side of said piston means, the third of which is adapted to admit fluid to the second side of said piston means, and the fourth of which is adapted to permit the flow of fluid from the first side of said piston means; said control means comprising photoelectric means for conveying operating impulses in response to movements of objects on said conveyor means, and step-by-step relay means having a first pair of relay points connected in parallel with each other and with said first and second circuits, respectively, and a second pair of relay points connected in parallel with each other and with said third and fourth circuits, respectively, said relay means conductively connected with said photoelectric means in such a manner that a first operating impulse transmitted by said photoelectric means energizes said first and second circuits to move the piston rod means in one direction whereby the loading members are pivoted into said first position, and that the next operating impulse transmitted by said photoelectric means energizes said third and fourth circuits to move the piston rod means in the other direction whereby the loading members are pivoted into said second position.

29. An apparatus as set forth in claim 7, wherein said pivoting means comprises double-acting cylinder and piston means on said frame, said piston means having a first side and a second side, piston rod means reciprocable by said piston means and articulately connected with one of said loading members, connecting means articulately fixed to said one loading member and to the other loading members for rotating the central loading member in anticlockwise direction when the first and third loading members rotate in clockwise direction in response to movement of said piston rod means in one direction and vice versa, a source of pressure fluid, a three-way magnet valve, and conduit means connecting said valve with said source and with said cylinder means at the first and second sides of said piston means, said valve comprising four energizable magnetic circuits the first of which is adapted to admit fluid to the first side of said piston means, the second of which is adapted to permit the flow of fluid from the second side of said piston means, the third of which is adapted to admit fluid to the second side of said piston means, and the fourth of which is adapted to permit the flow of fluid from the first side of said piston means; said control means comprising photoelectric means for conveying operating impulses in response to movements of objects on said conveyor means, and step-by-step relay means having a first pair of relay points connected in parallel with each other and with said first and second circuits, respectively, and a second pair of relay points connected in parallel with each other and with said third and fourth circuits, respectively, said relay means conductively connected with said photoelectric means in such a manner that a first operating impulse transmitted by said photoelectric means energizes said first and second

21

circuits to move the piston rod means in one direction whereby the loading members are pivoted into said first position, and that the next operating impulse transmitted by said photoelectric means energizes said third and fourth circuits to move the piston rod means in the other direction whereby the loading members are pivoted into said second position.

30. An apparatus for the deposition of substantially flat objects in substantially horizontal position in at least one stack as set forth in claim 1, wherein in the first position of said body portions said loading members define an upwardly opening compartment for reception of an object

22

in substantially vertical position, and wherein in the second position of said body portions the object first moves into substantially horizontal position and is finally released by the retaining means to drop from the second compartment.
